UNITED STATES PATENT OFFICE.

FREDERICK CIVIL, OF AUCKLAND, NEW ZEALAND.

MUSIC AND MANUSCRIPT HOLDER.

1,368,897.

Specification of Letters Patent. Patented Feb. 15, 1921.

Application filed October 21, 1920. Serial No. 418,387.

To all whom it may concern:

Be it known that I, FREDERICK CIVIL, of 12 Willisden road, Epsom, Auckland, in the Provincial District of Auckland, in the Dominion of New Zealand, a subject of the King of Great Britain and Ireland, declare that I have invented certain new and useful Improvements in Music and Manuscript Holders, of which the following is a specification.

This invention relates to devices used on pianos and similar instruments, music stands and the like for retaining sheets of music and the like, or the leaves of books, in the desired position to enable them to be read.

The object of the invention is to provide improved means for the aforesaid purpose, whereby the sheets or leaves may be readily secured and released without the employment of clips, screws, strings or other similar securing means.

In carrying out the invention the holder or frame on which the loose sheets or books are placed, has mounted thereon magnets, capable of being adjusted to suit sheets and books of various sizes.

Each sheet or leaf has attached thereto metal pieces adapted to be brought into contact with the magnets said metal pieces being located at or adjacent the vertical edges of the sheets, and the outer edges of the leaves of a book.

When it is desired to turn over a sheet or a leaf, the metal pieces are lifted from the magnets, said metal pieces after the sheet or leaf has been turned, making contact with the magnets at the opposite side of the holder or frame, to those from which they were freed.

In order that the invention may be more clearly understood it will be further described in conjunction with the accompanying drawing in which:—

Figures 1, 2 and 3 show holders or frames with magnets mounted thereon.

Figs. 4 and 5 illustrate different forms of magnets.

Fig. 6 shows by means of a sectional view the mounting of a magnet on the bar of the holder or frame.

Figs. 7 and 8 illustrate different forms of metal pieces capable of being attached to sheets or leaves, and

Fig. 9 is a diagrammatic view, showing

how electromagnets can be employed, with a circuit break, for de-magnetizing same when it is desired to turn over sheets or leaves.

The magnets 1 are permanently magnetized and may be shaped as shown in Figs. 1 to 5.

The music, manuscript 2 or the like which it is desired to retain on the holder or frame 3 has attached thereto at the corners, and in some cases also half way up the vertical edges, pieces 4 of thin steel.

The pieces 4 can be of any suitable shape, and may be in the form of tags or bars which project beyond the sheet or leaf 2, as in Figs. 3 and 8, or may be disks or the like located one at each side of the sheet or leaf 2 as in Figs. 1, 2 and 7.

A loose sheet of music or the like has a metal piece 4 at each corner, so that when placed on the holder or frame 3, the pieces 4 come in contact with and are attracted to magnets 1 at the corners of the holder or frame 3 and retain the sheet 2 securely thereon.

The sheet 2 is freed by merely lifting the pieces 4 from the magnets 1.

Music or the like in book form has metal pieces 4 at the outer corners only of each leaf, said pieces 4 coming in contact with and being attracted to the magnets 1 as before.

In order to turn a leaf the pieces 4 are lifted from the magnets 1, and after the leaf has been turned said pieces make contact with the magnets 1 at the opposite side of the holder or frame 3.

In order that the magnets 1 may be adjusted on the frame or holder 3 to suit the size of the sheets or leaves 2, they are provided with spring clips 5 which grip and are slideable on bars 6 capable of either vertical or horizontal adjustment on the holder or frame 3. Each magnet 1 is therefore capable of being moved horizontally and vertically on the holder or frame 3 as required.

A number of sheets or leaves 2 can be secured on the holder or frame 3 one against the other. When the metal pieces 4 are in the form of disks or the like on each side of the sheet or leaf, they stack against each other and in turn become magnetized and attract and retain the next disk or the like.

The metal pieces 4 when in the form of tags or bars projecting from the sheets 3 as

in Fig. 2 do not stack against each other, but are spaced so that each piece comes in actual contact with a magnet 1.

On holders or frames 3 used indoors, it is sufficient to have magnets 1 and metal pieces 4 at the upper corners only of the holder or frame 3, and sheets or leaves 2 respectively, and in this case the magnets 1 need only be adjustable toward and from each other.

10 Where the sheets or leaves 2 require to be more securely held, magnets 1 are employed at each corner of the holder or frame 3 and the sheets or leaves 2 have attached a similar number of pieces 4. It is necessary in the latter case that the magnets 1 be adjustable both vertically and horizontally.

If the music or the like is required to be more firmly held, as for instance when used out of doors, the sheets or leaves 2 can have 20 additional pieces 4 attached half way up their vertical edges and additional magnets 1 capable of being at least horizontally adjusted, are provided to suit.

Instead of being secured to the bars of 25 the holder or frame 3, by clips 5, the magnets 1 can be recessed in the bars 6 of said holder or frame, Fig. 3 in which case they are only capable of adjustment on moving the bar.

30 Instead of using permanent magnets 1 electromagnets 7, Fig. 9 can be employed, the latter being located in a circuit containing a battery 9 and a circuit breaker 10 kept normally closed by a spring 11. The circuit breaker 10 is located in any convenient position and when it is desired to demagnetize the magnets 7, the circuit breaker 10 is operated against the spring 11, by the foot, knee, or hand, leaving the sheet or 35 leaf 2 free to be turned. In a building having an electric installation the battery 9 is dispensed with and the magnets 7 are connected with the installation. A switch 8

for putting the circuit out of action when required is also provided.

45

What I do claim and desire to secure by Letters Patent of the United States is:—

1. A holder of the kind described, magnets mounted thereon, and metal pieces attached to the sheets or leaves supported by 50 said holder, adapted to make contact with said magnets, substantially as described and illustrated.

2. A holder of the kind described, magnets adjustably mounted thereon; and metal 55 pieces attached to the corners of the sheets or leaves supported by said holder, adapted to make contact with said magnets, substantially as described and illustrated.

3. A holder of the kind described, magnets slidable on bars adjustable on said holder; and metal pieces on each side of the corners of the sheets or leaves supported by 60 said holder, adapted to make contact with said magnets, substantially as described and illustrated.

4. A holder of the kind described, magnets slidable on bars adjustable on said holder; and metal tabs projecting from the sheets or leaves supported by said holder, 70 adapted to make contact with said magnets, substantially as described and illustrated.

5. A holder of the kind described, upper and lower magnets slidable on bars adjustable vertically on said holder, intermediate 75 magnets adjustable horizontally on said holder, and metal pieces on the sheets or leaves supported by said holder, substantially as described and illustrated.

In testimony whereof I have affixed my 80 signature in presence of two witnesses.

FREDERICK CIVIL.

Witnesses:

WILLIAM PINCHES,
MARY PICKINGTON.
